[57] CLAIM

The ornamental design for a frame support for a combined seat and table unit, substantially as shown and described.

DESCRIPTION

FIG. 1 is a front perspective view of a frame support for a combined seat and table unit, and showing my new design;

FIG. 2 is a top plan view thereof;

FIG. 3 is a front elevational view thereof;

FIG. 4 is a rear elevational view thereof;

FIG. 5 is a left side end elevational view thereof, as viewed in FIG. 1; and

FIG. 6 is a right side end elevational view thereof, as viewed in FIG. 1.

FIG. 2.

FIG. 4.

FIG. 5.

FIG. 6.
